OF PHILADELPHIA, PENNSYLVANIA, TRADING AS P. C. TOMSON &
COMPANY, OF PHILADELPHIA, PENNSYLVANIA.

CONVEYER-CHAIN FOR MATCH-MACHINES.

SPECIFICATION forming part of Letters Patent No. 698,526, dated April 29, 1902.

Application filed February 14, 1902. Serial No. 94,025. (No model.)

To all whom it may concern:

Be it known that I, EDWARD M. LOCKWOOD, Jr., of Darby, Delaware county, State of Pennsylvania, have invented an Improvement in Conveyer-Chains for Match-Making Machines, of which the following is a specification.

My invention has reference to conveyer-chains for match-making machines; and it consists of certain improvements fully set forth in the following specification and shown in the accompanying drawings, which form a part thereof.

The object of my invention is to so construct a conveyer-chain for match-making machines that it shall be light in weight, strong in construction, cheap in cost, and easily repaired when necessary.

My object is also to so form the match-making bars that they may be stamped by suitable dies from sheet-steel, with the result that they shall be practically unbreakable.

My invention primarily consists of a conveyer-chain built up of stamped bars having match-stick-carrying sockets. In carrying out my invention I form the conveyer of sections hinged together, each section consisting of a series of transverse bars having sockets for supporting the match-sticks connected to rack-bars near each end for connecting them together and for providing means to hinge such section to the next. The bars are of stamped sheet-steel and are provided with a series of semicircular portions driven outward to form sockets through which the match-sticks may be thrust and by which they are held and guided upon the bar. The sockets are thus formed without drilling, and as the bar is made by dies every bar is a counterpart of the other, and hence accuracy of construction is secured. The bars are flanged to secure strength, and the ends projecting beyond the rack-bars constitute sockets or teeth with which the teeth of the driving sprocket or gear wheels engage for propelling the conveyer as a whole.

My invention also consists of many details of construction, all of which will be better

understood by reference to the drawings, in which—

Figure 1 is a plan view of a portion of a conveyer-chain, parts being shown in section and dotted lines and also in its relation to the driving sprocket-wheels. Fig. 2 is a front elevation of a portion of same. Fig. 3 is an end view of same. Fig. 4 is a perspective view of a portion of one of the stamped sheet-metal bars making up the conveyer, and Fig. 5 is a section on line 5 5 thereof.

A A represent two sections of the conveyer-chain, the entire conveyer being made up of a very large number of such sections connected end to end to form an endless chain. Each section A consists of match-carrying bars D, arranged parallel and connected together by the end rack-bars B, which rack-bars of adjacent sections are hinged at b in any suitable manner. These rack-bars B consist of central body portions having long laterally-projecting lugs C between the hinge ends and short lateral lugs c adjacent to one of the ends. The bars D are substantially U-shaped in cross-section, having the horizontal flanges D' D'. The body portion at each end is slotted, as at d, to receive the body portion of the rack-bars between the projecting lugs C, as shown in Figs. 2 and 3, and intermediate of these slotted ends is provided with a series of outwardly-extending curved portions I, forced up out of the body of the bar, so as to produce a series of vertical apertures J for the reception of the match-sticks M. The lips of these outwardly-extending portions I are outwardly flared, as at i, though it is perhaps important that said outward flaring should be only on the lower lips or those directed toward the approaching match-sticks. However, by having both lips flaring the bars may be inverted, if desired. I also prefer to form the body of the bar with recessed portions K, above and below and in alignment with the outwardly-projecting portions I to better guide and hold the match-sticks parallel. To prevent the ends of the sticks catching upon the edge of the metal, the same is bent backward, as at k, forming

backward-flaring lips to the rear of projecting portions I. In this manner the match-sticks M are guided vertically through the apertures J without danger of catching upon the edges of the bar. The ends of these bars D are so shaped as to form rectangular sockets E, in which the teeth of the driving sprocket-wheels F engage, as shown in Fig. 1, the said sprocket-wheels rotating in a horizontal plane. The rear flanges D of the bars rest against the outer ends of the lugs C, as shown in Fig. 3, and are thus held in steady position upon the rack-bars. The rear bar of each section is held in position by a spring 15 G, which is sprung into position back of the bar and has its ends hooked, as at g, and hooked over the short lugs c of the rack-bars, as shown in Figs. 1 and 3. This spring also holds the rack-bars in place and prevents 20 them spreading toward the outer ends of the bars D.

It is seen that the cost of producing the bars D is much less than bars of cast or forged metal with the holes drilled and also that as 25 the bars are made with dies the position of every hole is definitely fixed. The bars being equally spaced apart produce in effect racks at their ends E to receive the driving-teeth of the sprocket-wheels F, and thereby obviate 30 the necessity of separate teeth either upon the bars D or upon the rack-bars B. The ends of the bars D are preferably rectangular, but the middle portions may have corners more or less rounded for more readily guiding the 35 match-sticks. The grooves K and the loops I form three places of support for the match-sticks in alinement, and hence the sticks are all held parallel and true.

I do not limit myself to the manner of connecting the series of bars D into a section or of connecting the sections, as these are details which may be modified or changed as desired; but the construction shown is simple and effective and excellently adapted to 45 the purpose of this invention. It also permits easy dismantling of the conveyer for repairs, so that very little loss of time is required in the operation of the machine even when repairs are required.

50 Having now described my invention, what I claim, and desire to secure by Letters Patent, is—

1. A conveyer for a match-machine consisting of longitudinal connecting-links and a series of transverse bars secured to the links, and consisting of stamped sheet metal, having a series of loops forced up from the face of the metal to form a support for the match-stick on one side and a series of guiding-surfaces on the face of the bars above and below the loops to form guiding-supports for the match-sticks on the other side.

2. A conveyer for a match-machine consisting of longitudinal connecting-links and a series of transverse bars secured to the links and consisting of stamped sheet metal having a series of loops forced up from the face of the

metal, to form a support for the match-stick on one side, and a series of guiding-surfaces on the face of the bars above and below the loops to form guiding-supports for the match-sticks on the other side, and in which the edges of the loops and the edges of the face metal back of the loops and bounding the last-mentioned guiding-supports are flared outward or away from the match held by said loops and guiding-supports.

3. A match-stick-supporting bar for a conveyer consisting of sheet metal having a bent flange for strength and having its body formed 80 with a series of outwardly-projecting looped portions pressed outwardly from the body.

4. A match-stick-supporting bar for a conveyer consisting of sheet metal having a bent flange for strength and having its body formed 85 with a series of outwardly-projecting looped portions pressed outwardly from the body and having their edges flaring outward as at i.

5. A match-stick-supporting bar for a conveyer consisting of sheet metal having a bent 90 flange for strength, and having its body formed with a series of outwardly-projecting looped portions pressed outwardly from the body and the metal of the body back of the loops flared outwardly in a backward direction as at k. 95

6. A match-stick-supporting bar for a conveyer consisting of sheet metal having a bent flange for strength and having its body formed with a series of outwardly-projecting looped 100 portions pressed outwardly from the body and the metal of the body above and below the looped portions inwardly grooved as at K, to guide the match-stick.

7. A match-stick-supporting bar for a conveyer consisting of sheet metal having a bent 105 flange for strength and having its body formed with a series of outwardly-projecting looped portions pressed outwardly from the body and the metal of the body above and below the looped portions inwardly grooved as at K to 110 guide the match-stick and having their adjacent edges flared outwardly backward as at k.

8. A match-stick-supporting bar for a conveyer consisting of sheet metal having a bent flange for strength and having its body formed 115 with a series of outwardly-projecting looped portions pressed outwardly from the body and further provided on their ends with slots d in the face.

9. A match-stick-supporting bar for a conveyer consisting of sheet metal having a bent flange for strength, and having its body formed 120 with a series of outwardly-projecting looped portions pressed outwardly from the body and further provided on their ends with slots 125 d in the face, combined with rack-bars fitting the said slots and having projections for supporting the flange portions of the bar.

10. A match-stick-supporting bar for a conveyer consisting of sheet metal having a bent flange for strength and having its body formed 130 with a series of outwardly-projecting looped portions pressed outwardly from the body and further provided on their ends with slots

d in the face, in combination with carrier-bars fitting said slots, and a spring connecting the carrier-bars and holding one of the supporting-bars in position.

5 11. A match-stick-supporting bar for a conveyer consisting of sheet metal having a bent flange for strength and having its body formed with a series of outwardly-projecting looped portions pressed outwardly from the body, 10 and having the ends made with sockets for receiving the teeth of driving sprocket-wheels.

12. A match-stick-supporting bar for a conveyer consisting of a channel-bar the intermediate body of which is provided with rounded projecting portions *I* forming apertures *J*, bounded on one side by said projecting portions and on the other by the body of the bar, and in which the body is grooved in 20 alinement with the aperture to properly guide the match-stick.

13. In a conveyer for a match-machine, a section comprising the rack-bars *B* having

lugs *C c*, combined with supporting-bars for the matches, having flanges *D* projecting loops 25 *I* and slots *d* into which the rack-bars fit and in which the flanges *D* rest against the lugs *C* of the said rack-bars.

14. In a conveyer for a match-machine, a section comprising the rack-bars *B* having 30 lugs *C c*, combined with supporting-bars for the matches having flanges *D* projecting loops *I* and slots *d* into which the rack-bars fit and in which the flanges *D* rest against the lugs *C* of the said rack-bars, and a spring *G* pressing 35 against one of the supporting-bars and looped over the lugs *c* of the rack-bars for holding them in the slots *d* of the supporting-bars.

In testimony of which invention I have 40 hereunto set my hand.
